UNITED STATES PATENT OFFICE.

ARTHUR L. GROTEWOHL, OF BURLINGTON, IOWA.

FAUCET FOR WASHBASINS.

SPECIFICATION forming part of Letters Patent No. 722,835, dated March 17, 1903.

Application filed June 23, 1902. Serial No. 112,878. (No model.)

To all whom it may concern:

Be it known that I, ARTHUR L. GROTEWOHL, a citizen of the United States, residing at Burlington, in the county of Des Moines and State 5 of Iowa, have invented a new and useful Faucet for Washbasins, of which the following is a specification.

This invention relates to washbasin-faucets.

The object of the invention is to provide a 10 faucet adapted for use either on the right or left hand side of a basin, by which arrangement the necessity of making faucets rights and lefts is obviated.

With these and other objects in view, as 15 will appear as the nature of the invention is better understood, the same consists, generally stated, in a faucet having its body portion provided with two threaded extensions of like diameters and disposed at right angles to each other, said extensions being adapted for interchangeable association with either the nozzle or the operating-handle according to the position the faucet occupies with relation to the basin, thereby always to 25 dispose the operating-handle at the front of the body portion, whether the faucet be arranged on the right or left hand side of the basin.

The invention consists, further, in the 30 novel construction and combination of parts of a faucet, as will be hereinafter fully described and claimed.

In the accompanying drawings, forming a 35 part of this specification, and in which like numerals of reference indicate corresponding parts, there is illustrated one form of embodiment of the invention capable of carrying the same into practical operation, it being understood that the elements therein exhibited 40 may be varied or changed as to shape, proportion, and exact manner of assemblage without departing from the spirit thereof.

In the drawings, Figure 1 is a view in perspective of a faucet constructed in accordance with the present invention. Fig. 2 is a view in vertical transverse section, taken through the nozzle. Fig. 3 is a similar view taken through the operating-handle.

The present invention is shown as applied 50 to what is known as the "Fuller" faucet; but it is to be understood that it is equally adapt-

able for use in connection with faucets of other styles, and for this reason the invention is not to be limited to the precise arrangement shown.

55

Referring to the drawings, 1 designates the body of the faucet, having its lower extremity exteriorly threaded for engagement with the usual supply-pipe 2, the said threaded end of the body being provided with the usual 60 valve-seat to be engaged by a valve 3. The body is provided with two bosses or extensions 4, disposed at right angles to each other and of like external diameter, the terminals of the bosses being externally threaded at 5 65 for engagement by unions 6 for holding the nozzle 7 and operating-handle 8 in operative position with relation to the body. The operating-handle is provided with the usual shank 9, having at its inner end a wrist-pin 70 10 to engage with an orifice in the upper end of the valve-stem 11, and the union that coacts with the valve-stem also subserves the function of a stuffing-box, as is usual. The nozzle 7, which may be of the construction 75 shown or otherwise, is provided at its inner end with a head 12, to be engaged by the union, thus to clamp it in position against the boss with which it coacts.

By having the bosses of like diameters it 80 will be readily seen that the operating-handle and nozzle may be shifted to accommodate the faucet to either the right or left hand side of the basin and by this simple expedient the necessity of duplicating the faucets for this 85 purpose, but with the nozzle and operating-handle transposed, as usual, is entirely obviated, thereby rendering it unnecessary for a plumber to carry a large stock of right and left hand faucets. Moreover, in washbasins 90 where only cold water is supplied the faucet is almost universally placed in the right-hand side, so that a plumber will always have on hand a large number of left-hand faucets that are useless. By the provision of the couplings changing of the nozzle and the operating-handle may be readily accomplished, and the presentation of tight joints will be readily effected, and with the nozzle the employment 95 of the union is particularly advantageous for 100 the reason that its adjustment may be positively effected with relation to the body with-

out the exposure of threads, such as frequently results where the nozzle is threaded into the body.

Having thus fully described my invention, 5 what I claim as new, and desire to secure by Letters Patent, is—

A faucet having its body portion provided with two threaded extensions of like diameter and disposed at right angles to each other, 10 and an operating-handle and a nozzle each

carrying a union adapted for interchangeable engagement with either of the extensions, substantially as and for the purpose specified.

In testimony that I claim the foregoing as my own I have hereto affixed my signature in 15 the presence of two witnesses.

ARTHUR L. GROTEWOHL.
